UNITED STATES PATENT OFFICE.

E. S. DAWSON AND A. WEEKS, OF SYRACUSE, NEW YORK.

OMNIBUS-REGISTER.

Specification of Letters Patent No. 31,788, dated March 26, 1861.

To all whom it may concern:

Be it known that we, E. S. DAWSON and A. WEEKS, of Syracuse, in the county of Onondaga and State of New York, have invented a new and Improved Omnibus-Register; and we do hereby declare that the following is a full, clear, and exact description thereof, reference being had to the accompanying drawings, making a part 10 of this specification, in which—

Figure 1 is a perspective view of the mechanism forming our improved omnibus register. Fig. 2 is a front view of the mechanism seen on removing the front of 15 the box containing it. Fig. 3 is a longitudinal section through the registering apparatus as indicated by the red line y, y , in Fig. 4. Fig. 4 is a transverse section through Fig. 3, in the vertical plane indicated by the red line z, z , in Fig. 3.

Similar letters of reference indicate corresponding parts in the several figures.

This invention relates to an improvement in registers for city cars, omnibuses &c., for 25 registering the number of passengers entering the same.

The object of this invention is to furnish city cars, omnibuses &c., with a registering apparatus which is placed under the control 30 of the driver or conductor, who is instructed to register the entrance of each passenger, said register is to be provided with an alarm which will serve as a tell-tale to the passengers in the conveyance, and it 35 is also to be placed in a prominent situation where it can be seen and read by the passengers.

Our invention consists in a novel combination of wheels or cylinders and counter 40 wheels each possessing a certain numerical value, with certain pawls and ratchets which are arranged on a rocking frame operated by a lever to which the driver's strap is connected, as will be hereinafter described.

Said wheels, ratchets and pawls being 45 arranged within a suitable box with a glass window in front exhibiting the numbers on the wheels, all as will be herein fully explained.

To enable those skilled in the art to make and use our invention we will proceed to 50 describe its construction and operation.

A. is an iron plate from the ends of which 55 project out, perpendicularly to the face of this plate, two standard supports a, a' ; and

between these two standards a, a' , is another standard b .

B. is a fixed shaft on which the drums or wheels C. and D. have their bearings. This shaft B. has its end bearings in the 60 standards a and b , and the set screws c, c , secure this shaft rigidly to the said standards.

E. is a short shaft which serves as a bearing for the wheel G. This shaft E. 65 has its end bearings in the two standards b , and a' , and as standard a' , is a little in advance of the standard b , the axes of the two shafts B. E. are not in a straight line, but the shaft E. forms an obtuse angle with 70 shaft B. This shaft E. is also stationary while the wheel G. turns on it.

The drum C. consists of a ratchet wheel e , which projects from one end, an elevated surface f , and a depressed surface g . The 75 drum D. consists of an annular flange or ring h , a ratchet wheel i , and a cylindrical portion k , which latter portion passes over the portion g , of drum C. as represented in Fig. 3 of the drawings. A portion of the 80 cylinder k , of drum D. is cut out as represented in Fig. 2, the object of which will be hereinafter explained.

The wheel G. is of the form of the frustum of a cone, and this wheel has a ratchet 85 wheel l , projecting from one end as shown in Figs. 1, 2 and 3, of the drawings. The flaring edge of this wheel G. touches the drum D. in front, but on account of its obliquity to the axis of the shaft B. there is a 90 space left between the flaring edge of this wheel G. and the edge of wheel D. at the back sufficient to allow three pawls to work between the wheel and drum as represented in Fig. 1 of the drawings. 95

The peripheries of the two drums C. D. and that of the wheel G. have numbers painted or engraved on them which will be hereinafter described; and these numbers are brought opposite each other at a point 100 behind the window j , which is represented in Fig. 4, so as to indicate units, tens, and hundreds by a novel arrangement of pawls or detents operating alternately and in regular succession upon the drums C. D. and wheel G. at proper intervals as will be herein described.

H. is a right angular rocking frame the two arms of which are pivoted at n, n , to the standards a, a' , Figs. 1 and 2. From 110

the end of one of the arms of frame H. proceeds up a lever I. with a ring or eye on its upper end.

J. is a coiled spring which holds lever I. back and keeps the frame H. in the position represented in Figs. 1, 2, 3 and 4, of the drawings, when the lever is not otherwise acted upon.

The back part or longitudinal bar of frame H. carries a number of spring pawls which engage with their respective ratchet wheels at proper times and give motion to the drums C. D. and wheel G. when the lever J. is drawn forward and the frame H. is rocked upon its pivots.

The drums C. D. and wheel G. are prevented from rotating backward by friction springs p, p, p, which are secured to the bed A. and press against the peripheries of their respective drums and wheel.

The wheel G. is operated by a pawl r, which is pivoted to a pawl bar r', and acted upon by a spring r². This pawl r engages with the teeth l, on wheel G. and gives the wheel G. a turn equal to the length of the ratchet teeth. On the inside of wheel G. is a circular plate K. having a notch cut into its edge as represented in Figs. 1 and 3 of the drawings, and on the edge of this plate K. rests the end of an arm s, which is fixed to the pawl bar r'. This arm s, is held against the edge of plate K. by the spring s'; s² is a pawl which is also fixed to the bar r', and which is intended to engage with the ratchet teeth of drum D. and rotate this drum the distance of one tooth at each revolution of the wheel G. To effect this result the end of arm s, drops into the notch in plate K. at each revolution of wheel G. and thus depresses the end of pawl s², so that this pawl will engage with the ratchet teeth, then at the next movement of wheel G. the arm s, is elevated out of its notch in plate K. and the pawl s², is raised sufficiently to clear the teeth of the ratchet wheel. The wheel G. then makes another revolution before the pawl s², is again brought into action. The drum C. is operated by a pawl t, acted upon by spring t', which pawl engages with the teeth of ratchet e, at a proper time viz: when the drum D. has made one revolution.

Pawl t, is operated so as to engage with, and rotate, the drum C. the distance of one tooth at each revolution of the drum D. by a hooked arm v, the end of which is held against the ring or flange of the drum D. by the spring t', and at each revolution of drum D. the hooked end of arm v, drops into a notch in ring or flange h and thus brings the end of pawl t, against one of the teeth of ratchet e so that when the frame H. is raised by lever J. the pawl t, will rotate the drum C. the distance of one tooth, as above described.

When pawl t, drops and is in a position to operate upon its ratchet teeth, the pawl s², and also pawl r, are in a position to operate upon their respective ratchets, and the two drums C. D. and wheel G. are moved simultaneously. When the frame H. is now depressed the arm s, is moved out of its notch in plate K. and the pawl s², is also raised and disengaged from its ratchet.

At the same time that the pawl s², is raised a short arm w, which projects from this pawl raises and disengages the arm v, and pawl t, from their respective drums, by raising the arm v, out of its notch in flange h, on the surface of this flange again where it remains until the wheel D. makes another revolution.

It will now be seen from the foregoing description that when wheel G. makes one revolution, drum D. is moved the distance of one ratchet tooth, and when drum D. has made one revolution the drum C. is turned the distance of one ratchet tooth.

The above described mechanism is all arranged within a suitable box N. having a window j, in front and this box is secured in a prominent situation in the omnibus or car, and a strap—which connects with lever I.—is carried off to a place where it can be conveniently operated by the driver, or the conductor. In the top of box N. a small bell may be arranged which will be operated by an arm resting on the ratchet teeth l, of wheel G. so that at every movement of this wheel G. an alarm will be sounded, which will notify the passengers in the conveyance that the driver has attended to his duty of registering each passenger entering the conveyance. This alarm bell will be more especially useful at night when the passengers would not be apt to notice the registering figures.

The operation of our improved registering apparatus is as follows: Let it be supposed that the registering apparatus is in a position to be seen by all the passengers in the car, or omnibus, and that a strap which is attached to lever I. is carried off so as to be convenient for the driver to pull it. The drums and wheels are all arranged at the starting so as to indicate cipher, as represented in Fig. 2. The first passenger who enters the conveyance is registered by the driver, who pulls the strap connected to lever I. This lever raises the frame H. and causes the pawl r, to rotate the wheel G. the distance of one ratchet tooth l, and bring the number one behind the window j. There are ten ratchet teeth l, on this wheel G. and ten numbers corresponding to the teeth; and when ten passengers have entered the conveyance,—the driver pulling the strap once for each passenger,—the wheel G. will have made one revolution and the drum D. will be moved once by the pawl s², thus

bringing the number one on drum D. opposite or at the left of the cipher on wheel G., reading ten. At the next revolution of wheel G. the arm s_1 will fall into the notch 5 in plate K. and cause the pawl s^2 , to move drum D. the distance of another tooth causing it to register with the cipher on wheel G. number twenty, and so on until the drum D. has made one revolution, when the arm 10 v , will drop into the notch in flange h, of drum D. and cause the pawl t, to act upon drum C. at the next movement of the lever I. This drum C. together with drum D. and wheel G. will now indicate one hundred. 15 Thus it will be seen that at every revolution of wheel G. the drum D. will be moved one tenth of a revolution, and at every revolution of drum D. the drum C. will be moved one tenth of a revolution. The wheel G. 20 registers units, the drum D. tens and the drum C. hundreds. The depressed surface g, of the drum C. contains ten ciphers one

of which is brought to view at each revolution of the drum D. The spring J. operates upon lever I. and returns the frame H. with 25 its pawls, springs and arms back to their original positions, after the strap, which is attached to lever I., is released.

Having thus described our invention what we claim as new and desire to secure by Letters Patent is—

The arrangement of vibrating frame H. with ratchets r , s^2 , and t, and arms s , v , and w , friction springs p , p , p , in combination with drums C. and D. wheel G. all constructed and operating to produce a numerical series by revolving wheels substantially as and for the purposes herein specified.
